CALCULATING MACHINE CASING

Frederick A. Niemann, Chicago, Ill., assignor to
Felt & Tarrant Mfg. Co., Chicago, Ill., a cor-
poration of Illinois

Application October 1, 1938, Serial No. 232,782

3 Claims. (Cl. 235—61)

This invention relates in general to calculating machines, and more particularly to a new and improved casing therefor.

The instant invention is particularly adapted for use with a key-controlled calculating machine, such as those disclosed in the patent to J. A. V. Turck No. 2,063,962, granted December 15, 1936, although it will be readily understood that it may be employed with any desired type of machine. Heretofore, as particularly illustrated in said patent, it has been customary to make the top, bottom and each wall of the casing of a calculating machine as a separate part, and to join the several parts together by means of screws, or the like. This necessitated the drilling and tapping of numerous holes, extensive handling of the several parts, and the use of various jigs and the like in the manufacture and assembly of the casing.

A principal object of the invention, therefore, is the provision of a casing for a calculating machine which is made up of only two parts, a base and a five-walled cover portion, and is thus easy to manufacture and assemble, and reduces the amount of material and the number of operations and tools heretofore necessitated.

Another important object of the invention is the provision of a calculating machine casing having a flat portion in which sight apertures are formed, through which the numeral wheels are visible, and which is so angularly disposed relative to the base of the casing as to be perpendicular to the normal line of vision of an operator during operation of the machine.

A further important object of the invention is the provision of a calculating machine casing in which the side walls have longitudinally disposed indentations or recessed portions therein which constitute hand holds to facilitate lifting and moving of the machine.

Another object of the invention is the provision of a casing for a calculating machine in which all fastening means for securing the parts of the casing together and for securing the mechanism of the machine to the base of the casing are completely hidden from view when the machine is in normal or operating position.

Numerous other objects and advantages of the invention will be apparent as it is better understood from the following description, which, when taken in connection with the accompanying drawings, discloses a preferred embodiment thereof.

In the drawings,

Figure 1 is a perspective view of a calculating

machine casing embodying the features of my invention;

Fig. 2 is a side elevation of the casing of Fig. 1;

Fig. 3 is a transverse sectional view of the casing; and

Fig. 4 is a horizontal section taken substantially on the line 4—4 of Fig. 2.

Referring more particularly to the drawings, reference numeral 11 indicates in general the 10 casing of a calculating machine which comprises a hollow cover portion 12 and a base 13. The cover portion 12 is preferably stamped and deep-drawn, by means of suitable dies, from any desired light weight material, and comprises a top 15 wall 14, sloping or curved front and rear walls 15 and 16, respectively, and side walls 17. These several walls are formed as a unitary structure from a single piece of metal, which results in maximum rigidity of the casing and the elimination of all means for securing the walls together, while greatly enhancing the visual appearance of the casing.

The top wall 14 of the cover 12 comprises a 20 pair of longitudinally disposed marginal portions 18 bordering a central raised portion 19. The central portion 19 is provided with a substantially rectangular aperture 21 through which the digital control keys of the machine (not shown) are 25 adapted to extend. When the machine is wholly assembled, the cover plate of the key carrying frame (not shown) is positioned directly below the central portion 19 of the top wall of the casing and completely closes the aperture 21. The right hand marginal portion 18 (viewing Fig. 1) 30 may be provided with a longitudinal slot 22 and a hole 23, through which the canceling or zeroizing lever and the correction key, respectively, (neither of which are shown in the drawings) extend when the machine is completely assembled. It will be noted that the top wall 14 of 35 the casing slopes downwardly from the rear to the front of the machine (from right to left, viewing Fig. 2), which is done for the purpose of having the keyboard positioned most advantageously for the operator.

The marginal portions 18 of the top wall 14 40 continue forwardly and rearwardly into the upper curved portions 24 and 25, respectively, of the front and rear walls 15 and 16 (Fig. 2). The rear end of the raised portion 19 of the top wall 45 continues into a curved portion 26 of the rear wall 16, which is spaced outwardly from the curved marginal portions 25 the same distance as obtains between the portions 18 and 19 of the top wall. These curved portions continue in

their same spaced relationship into the vertical part of the rear wall, as will be seen in Fig. 4, with the central panel 26 terminating at its lower end short of the lower ends of the marginal portions 25 (Fig. 2), for a purpose to be later described.

The forward end of the central portion 19 of the top wall 14 terminates in a flat portion 27 (Fig. 1) which is preferably disposed at an angle of approximately 32° to the horizontal, and continues in tangential relationship directly into the curved portion 24 of the front wall 15 (Fig. 2). The flat portion 27 is provided with a plurality of transversely spaced sight apertures 28 through which a particular numeral on each of the individual numeral wheels (not shown) of the several denominational orders of the accumulator will be visible when the calculating machine is completely assembled. The numeral wheel sight apertures 28 are thus disposed in a flat surface, which prevents distortion of vision, and in a plane which is perpendicular to the normal line of vision of the machine operator.

Each of the side walls 17 of the cover part 12 of the casing is provided with a curved marginal portion 29 which follows the longitudinal cross sectional contour of the front wall 15 and the marginal portions 18 and 25 of the top and rear walls, respectively, and is joined thereto by a curved shoulder portion 31. A longitudinally disposed indentation or recessed portion 32 is provided in each side wall 17 adjacent the top thereof, which is substantially V-shaped in vertical cross section (Fig. 3), and the upper edge of which is uniformly spaced from the curved shoulder portion 31 so that it follows the contour of the top and end walls of the casing. These indentations 32 constitute hand holds at each side of the machine to facilitate lifting and moving the same, as well as adding materially to the appearance thereof.

The lower end of each of the front and rear walls 15 and 16 and side walls 17 terminates in an inwardly or horizontally extending flange or shoulder 33 (Figs. 3 and 4), which is bent upwardly at its inner end to provide a vertical flange 34 spaced inwardly from its associated wall member. The longitudinal ends of the several flanges 33, 34 terminate short of the curved, vertical corner portions of the cover part 12 of the casing, as will be seen best in Fig. 4, and the latter extend downwardly flush with the lower surfaces of the flanges 33. It will be understood that the curved corner portions referred to constitute the ends of the marginal portions 29 of the side walls 17 and the curved shoulders 31. At selected points, each of the associated flanges 33, 34 is bent inwardly to provide an enlarged portion or pocket 35. A suitable aperture is provided in each of the flanges 33 substantially centrally disposed relative to each of the pockets 35.

The base 13 of the casing 11, like the cover member 12, is formed as a unitary member from any suitable light weight material, and comprises a substantially rectangular plate 36 with rounded corners which is bounded on all sides by a continuous, upstanding vertical flange 37. The flange 37 is preferably corrugated or beaded horizontally, and terminates in an inwardly curved or rounded top edge which is adapted to slidably engage and fit tightly against the outer surface of the cover member 12 of the casing. The corrugations add to the strength of the flange 37 to prevent it being bent out of shape and out of the desired close contact with the

cover member 12, as well as enhancing the visual appearance of the casing as a whole.

Along each of its four sides and in inwardly spaced relationship to the flange 37, the plate 36 is provided with a relatively narrow shoulder 38 which terminates short of the rounded corner portions of the flange 37 and is formed as a recess or indentation stamped into the plate and extending upwardly from the plane thereof and having an inverted U-shaped cross section (Fig. 3). These shoulders 38 are so positioned that the flanges 33 of the cover part 12 will rest directly thereon and substantially coincide therewith, when the two parts of the casing are in their assembled position of the drawings. Suitable apertures therefore are provided in the top walls of the several shoulders 38 so as to coincide with the apertures in the bottom walls of the pockets 35.

The vertical flanges 34 are broken away adjacent the central portion of each of the pockets 35, and the resulting end portions 39 thereof are bent outwardly (Fig. 4), after suitable elongated nuts 40 have been disposed in the pockets 35, to prevent the nuts from being displaced upwardly out of the pockets. The nuts 40 are provided with suitable inward extensions adjacent their centers which are substantially the same shape as the pockets 35 and prevent them from moving longitudinally out of the pockets. Thus, with the cover part 12 properly positioned on the base 13, suitable screws extending through the apertures in the shoulders 38 and screwed into the nuts 40 will securely retain the two parts of the casing 11 together.

The plate 36 of the base 13 is also provided with a plurality of upwardly extending, circular indentations or projections 41 stamped or otherwise formed therein, each of which has a suitable hole or aperture in the top wall thereof. The skeleton frame members of the internal mechanism of the calculating machine (not shown) have feet or tabs which are adapted to rest on these projections 41 and be rigidly secured thereto by suitable screws extending upwardly through the projections, with their heads being disposed in the lower portions thereof above the bottom surfaces of the plate 36. In this manner, the mechanism of the machine may be secured to the base 13 of the casing 11, after the cover part 12 has first been properly positioned over the mechanism, with the keys extending upwardly through the top wall 14 and the cover plate of the key carrying frame closing the aperture 21. Then the screws may be inserted, as above described, to secure the cover part 12 to the base 13 of the casing 11.

A plurality of projections 42, similar to the projections 41, also may be provided on the plate 36 of the base 13, within the lower portion of which suitable resilient pads for supporting the machine may be secured in any desired manner. With the casing 11 constructed as above described, the mounting of sheets of suitable sound deadening material upon the inner surfaces thereof is very greatly facilitated. The flanges 34 function to retain the lower ends of vertically disposed sheets of the sound deadening material, and suitable flanges 43 (Figs. 2 and 3) may be welded or otherwise secured to the inner surfaces of the walls 15, 16 and 17 for retaining the upper ends of said sheets. Since the shoulders 38 and projections 41 and 42 are raised above the main part of the plate 36, a space is also provided

thereon which may readily be filled with the sound deadening material.

It will be apparent that the calculating machine casing herein disclosed presents a smooth and finished appearance of substantially unbroken or continuous surfaces, and that all fastening means for securing the two parts of the casing together and for securing the mechanism of the machine to the base of the casing are completely hidden from view when the machine is in normal or operating position. At the same time, the sight apertures for the numeral wheels are in that position which is most easily observable by the machine operator. Since the casing is made in only two parts, the manufacturer and assembly thereof is greatly facilitated, particularly because of the reduction in the amount of material and the number of operations and tools which has thus been effectuated.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A casing for a calculating machine, or the like, comprising a unitary base member having a marginal flange extending upwardly therefrom, shoulder members spaced inwardly from said flange and above the plane of said base member and formed integrally therewith, a multi-walled

cover member having inwardly extending flanges formed integrally with the walls thereof and resting upon said shoulders, and means operable from beneath said base member securing said shoulders and said inwardly extending flanges together, whereby said means are completely concealed from view when said casing is in normal position, the marginal flange of said base member fitting snugly around the lower portion of said cover member.

5 2. A casing for a calculating machine, or the like, comprising a sheet metal base member having upstanding substantially inverted U-shaped shoulders formed integrally therewith, a unitary, sheet metal, multi-walled cover member having inwardly extending flanges formed at the lower ends of some of the walls thereof, and means confined within an offset portion of said shoulder for rigidly securing said flanges and said shoulders together, thereby rendering the securing means non-visible.

15 3. A casing for a calculating machine, or the like, comprising a unitary base member having a marginal flange extending upwardly from each 25 edge of the said base member, and an upstanding shoulder formed adjacent each of said flanges, said flanges extending above the level of said shoulders, and a unitary, sheet metal, multi-walled cover member having inwardly extending flanges formed at the lower ends of the 30 walls thereof, said latter flanges coinciding with said shoulders and being rigidly secured thereto, and the vertical walls of said cover member being in contact with the flanges of said base member.

FREDERICK A. NIEMANN.
